(57) **CLAIM**

The ornamental design for a seed dibber, as shown and described.

DESCRIPTION

FIG. 1 is a perspective view of a seed dibber showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1; FIG. 10 is an enlarged view of portion 10 shown in FIG. 5; and,

FIG. 11 is an enlarged view of portion 11 shown in FIG. 7. The dash-dash broken lines in the drawings depict portions of the seed dibber that form no part of the claimed design. The dot-dash broken lines represent boundary of the enlarged portion and form no part of the claimed design.

1 Claim, 11 Drawing Sheets
